[57] CLAIM

The ornamental design for a locking assembly for a door, as shown and described.

DESCRIPTION

FIG. 1 is a front elevational view of a locking assembly for a door showing my new design, the broken lines being for illustrative purposes only;

FIG. 2 is a top plan view thereof;

FIG. 3 is a left side elevational view thereof;

FIG. 4 is a right side elevational view thereof;

FIG. 5 is an enlarged top plan view of the center bolt lock of the assembly, the bottom being substantially a mirror image thereof;

FIG. 6 is a left end elevational view of FIG. 5;

FIG. 7 is a front elevational view of FIG. 5;

FIG. 8 is a right end elevational view of FIG. 5;

FIG. 9 is a rear elevational view of FIG. 5;

FIG. 10 is an enlarged top plan view of either the upper or lower bolt lock of the assembly, the bottom being substantially a mirror image thereof;

FIG. 11 is a left end elevational view of FIG. 10;

FIG. 12 is a front elevational view of FIG. 10;

FIG. 13 is a right end elevational view of FIG. 10;

FIG. 14 is a rear elevational view of FIG. 10;

FIG. 15 is an enlarged top plan view of the center strike plate of the assembly, the bottom being substantially a mirror image thereof;

FIG. 16 is a left side elevational view of FIG. 15;

FIG. 17 is a front elevational view of FIG. 15;

FIG. 18 is a right side elevational view of FIG. 15;

FIG. 19 is a rear elevational view of FIG. 15;

FIG. 20 is an enlarged top plan view of either the upper or lower strike plate of the assembly, the bottom being substantially a mirror image thereof;

FIG. 21 is a left side elevational view of FIG. 20;

FIG. 22 is a front elevational view of FIG. 20;

FIG. 23 is a right side elevational view of FIG. 20; and

FIG. 24 is a rear elevational view of FIG. 20.
